GEOEGE WASHINGTON GRUVER, OF PACIFIC GROVE, CALIFORNIA, ASSIGNOR OF ONE-HALF TO CHRISTIAN H. WIDEMANN, OF GONZALES, CALIFORNIA.

CLEANER-ROD FOR GUNS.

1,175,256.

Specification of Letters Patent. Patented Mar. 14, 1916.

Application filed October 13, 1914. Serial No. 866,507.

To all whom it may concern:

Be it known that I, GEORGE W. GRUVER, a citizen of the United States, residing at Pacific Grove, in the county of Monterey and State of California, have invented a new and useful Cleaner-Rod for Guns, of which the following is a specification.

The present invention relates to improvements in cleaner rods for guns, one object 10 of the invention, being the provision of a telescopic sectional rod, the incasing section of which is the cleaner carrying member, so that when the rod is inserted within the gun, there are no rigid shoulders to engage the 15 edge of the barrel as is the case where the cleaner carrying member is the smaller member of the rod.

A further object of the present invention, is the provision of a telescopic sectional rod 20 in which the coöperating ends are provided with screw threads so that when the sections are extended and locked, a rigid rod is provided, certain of the sections being provided with further coöperating means to lock certain 25 of the sections against rotation during the releasing of the screw threaded portion when collapsing the sections.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed can be made within the scope of what is claimed without departing from the spirit of the invention.

In the drawings—Figure 1 is a side elevation of the complete rod extended. Fig. 2 is 40 a longitudinal sectional view through the tubular sections of the rod showing the parts collapsed, portions of the handle carrying section being shown in section to illustrate the connection thereof with the handle.

Fig. 3 is a section taken on line 3—3 of Fig. 2. Fig. 4 is a section taken on line 4—4 of Fig. 2. Fig. 5 is an enlarged detached perspective view showing the manner of connecting the two tubular sections together 50 when the parts are extended. Fig. 6 is an enlarged detail view showing the position of the parts, when the intermediate telescopic section is collapsed, and the portion adjacent the handle. Fig. 7 is an end view

of the cleaner tool carrying plug, looking 55 from the inner end thereof.

Referring to the drawings, the numeral 1 designates the handle or hand grip, which is socketed at 2 to receive the threaded portion 3 of the main and reduced carrying rod 60 5, the pin 4 being extended through the rod within the handle portion to lock the same against rotation. This rod 5 has slidably mounted thereupon, an incasing intermediate tubular section 6, one end of which is 65 tapered as at 7 and is provided with the diametrical slots 8 which coöperate with the lugs 9 carried by the handle member when the section 6 is collapsed when the section 14, as will presently appear, is still threadedly engaged with the section 6. The member 6 adjacent the reduced portion 7 is provided with the interior screw threads 10 which are adapted to coöperate with the screw threads 11 of the rod 5 when the section 6 is extended, while the exterior screw threads 12 formed upon the opposite end of the section 6 coöperate with the interior screw threads 7 of the reduced end of the main inclosing or telescoping member or 80 section 14. Thus when the parts are extended and the respective threads 10—11 and 12 13 are engaged, the rod will assume the condition, as shown in Fig. 1, the parts being rigidly locked by the screw threads so 85 that a rigid rod is provided, the section 14 being the cleaner carrying section so that when the same is introduced within the gun, the reduced ends of the sections 14 and 6 will ride over or past the outer end of the 90 gun barrel without injuring or marring the same. When the sections are reversed, so that the reduced section 5 would be the section to be first introduced, it is apparent that the shoulders formed at the connection 95 of the respective sections would form an abutting means that would render it practically impossible to introduce the cleaner within the barrel without striking and marring the mouth thereof.

Fitted within the outer end of the section 14 is the plug 15, the same being held against rotation by means of the pin 16, the plug being provided with a reduced portion 17 which has the diametrically disposed lugs 18 for registration with the diametrically disposed recesses 19 of the section 6, so that such section 6 may be col- 100 105

lapsed within the section 14 and be held against rotation should the threads 10 and 11 hold after the threads 12 and 13 have become disengaged during the collapsing 5 of the sections.

In order to provide a means for locking the sections as shown in Fig. 2, the outer end of the rod 5 is provided with the screw threads 20 insertible within the screw 10 threads 21 of the plug 15, these screw threads not engaging until the sections have been thoroughly collapsed to their fullest extent.

Adapted to fit within the outer end of the 15 plug 15 is the cleaner member 22, which may be taken indicative of any form of member insertible therein.

From the foregoing description, the operation 20 and construction of the present rod is fully understood, but in order to briefly set forth the operation of the same, it will be assumed that the parts are in the position as shown in Fig. 2 and it is desired to extend to the position as shown in Fig. 1.

25 The operator by gripping the handle 1 and the tubular section 14, rotates either so that the threads at 20 and 21 disengage and thus permit the extension of the sections 14 and 6 sufficiently to permit the threads 12 and 30 13 to be placed in engagement, at which time, the section 6 is grasped while the section 14 is rotated. After these threads have been engaged to the desired extent, the threads 10 and 11 are placed in engagement 35 by gripping the handle 1 and rotating the section 6 through the section 14.

In order to collapse the sections from the position shown in Fig. 1 to that shown in Fig. 2, the operator grips the handle 1 and 40 the section 14 and rotates the same to disengage either one of the threads 10 and 11 or 12 and 13. Should the threads 10 and 11 disengage first, the section 6 will be collapsed so that the recesses 8 will engage the 45 lugs 9 and thus lock the section 6 against rotation or fast with the handle 1, at which time, the tubular section 14 is continued rotating to disengage the threads 12 and 13, the same permitting the collapsing of the 50 section 14 to its fullest extent or until the threads 20 and 21 are engaged to lock the sections as shown in Fig. 2. Should the threads 12 and 13 become disengaged before those at 10 and 11, the section 14 will then 55 collapse upon the section 6, bringing the lugs 18 into registration with the recesses 19 so that the section 6 can then be rotated through the instrumentality of the section 14 to disengage the threads 10 and 11.

60 What is claimed is:

1. A gun cleaning rod including a handle, a rod extending therefrom, there being threads upon the rod adjacent the handle,

and spaced threads outstanding from the outer end portion of the rod, an intermediate tubular member slidably mounted on the rod and having an interiorly threaded end portion for engaging the threads on the rod adjacent the handle, there being exterior threads upon said intermediate tubular member at that end thereof farthest from the handle, an outer tubular member adapted to house the intermediate tubular member and having interior threads at one end for engaging the exterior threads upon the intermediate tubular member, a plug connected to the outer end of said outer tubular member and having a threaded bore adapted, when the cleaner rod is collapsed, to receive one of the spaced threads on the 80 rod, thereby to hold the outer and intermediate tubular members against sliding movement relative to the rod and to each other, and a cleaner member connected to and extending outwardly from the plug. 85

2. A gun cleaning rod including a handle, a rod extending therefrom, there being threads upon the rod adjacent the handle, and spaced threads outstanding from the outer end portion of the rod, an intermediate tubular member slidably mounted on the rod and having an interiorly threaded end portion for engaging the threads on the rod adjacent the handle, there being exterior threads upon said intermediate tubular member at that end thereof farthest from the handle, an outer tubular member adapted to house the intermediate tubular member and having interior threads at one end for engaging the exterior threads upon the intermediate tubular member, a plug connected to the outer end of said outer tubular member and having a threaded bore adapted, when the cleaner rod is collapsed, to receive one of the spaced threads on the 90 rod, thereby to hold the outer and intermediate tubular members against sliding movement relative to the rod and to each other, and a cleaner member connected to and extending outwardly from the plug, 95

100 one of the spaced threads upon the rod constituting means for engaging the interior threads of the intermediate member to hold said member extended relative to the rod, and co-operating means upon the handle 110 and outer member for holding the said member against rotation relative to the handle 115 when the cleaning rod is collapsed.

In testimony that I claim the foregoing as my own, I have hereto affixed my signature in the presence of two witnesses.

GEORGE WASHINGTON GRUVER.
